ARROW CONTAINER

Wenzell S. Hoffman, Lake Orion, Mich.

Application February 6, 1956, Serial No. 563,636

1 Claim. (Cl. 150—1.5)

This invention relates to hunting arrow quivers, and, more particularly, to an arrow quiver especially adapted to be carried on the back of a hunter and to support a plurality of arrows in an easily accessible position.

At the present time, there are hunting arrow quivers on the market which are adapted to be carried on the back of a hunter, but they have certain disadvantages and drawbacks, as, for example, the arrows are mounted in said quivers with the tuft or rearward ends thereof projected upwardly, adjacent the back of the head of the hunter. With such a quiver, the hunter must reach backwardly and over his shoulder to grasp the arrow, and, this movement is very awkward and difficult to make, especially at various times when the hunter is in the woods and has need of an arrow in a hurry so as to make a shot at game that may have appeared suddenly.

A further disadvantage of the prior art type arrow quivers is that the brightly-colored tufts of the arrows are carried high up in the air, adjacent the rearward side of the head of the hunter, and, this provides a distraction as the hunter moves through the forest, which has the effect of scaring the game away. Accordingly, it is a primary object of this invention to provide a hunting arrow quiver which overcomes the aforementioned disadvantages, and, which is adapted to carry a plurality of arrows with the tufts disposed toward the lower end of the quiver which is carried in a vertical position on the back of a hunter.

It is another object of the invention to provide a hunting arrow quiver which is adapted to be detachably mounted on the back of a hunter, and, in which the arrows are vertically disposed with the heads of the arrows upwardly and the tufts downwardly, whereby, the hunter may remove an arrow from the quiver by merely placing his hand at his side and moving it backwardly and to the rear of his body, whereby, his hand will then be adjacent the tufts of the arrows, and, an arrow may be easily and quickly removed from the quiver by merely grasping the lower end of an arrow and bringing the hand downwardly and forwardly to the front of the body so that the arrow ends up in a position ready for proper orientation or positioning in the bow and for instant shooting thereof.

It is a further object of this invention to provide a hunting arrow quiver which will be light of weight, simple and compact in construction, adjustable in length, economical of manufacture, and, efficient in use.

It is still another object of this invention to provide a hunting arrow quiver comprising: an upper head and a lower head, which are spaced apart and which are provided with a covering of sponge rubber on the inner adjacent sides thereof, an adjustable elongated support fixedly connecting said heads together, socket means on said sponge coverings adapted to releasably hold the head and tuft ends of a plurality of arrows, a covering means for covering the arrows when they are mounted

2

in said sockets, and, means for detachably fastening said quiver to the back of a hunter.

Other objects, features and advantages of this invention will be apparent from the following detailed description and appended claim, reference being had to the accompanying drawing forming a part of the specification wherein like reference numerals designate corresponding parts of the several views.

In the drawings:

10 Fig. 1 is a perspective view of a quiver made in accordance with the invention, and shown in a mounted position on the back of a hunter;

15 Fig. 2 is an elevational sectional view of the structure illustrated in Fig. 3, taken along the line 2—2 thereof;

15 Fig. 3 is a horizontal sectional view of the structure illustrated in Fig. 2, taken along the line 3—3 thereof;

Fig. 4 is a horizontal partial sectional view of the structure illustrated in Fig. 2, taken along the line 4—4 thereof; and

20 Fig. 5 is a horizontal sectional view of the structure illustrated in Fig. 2, taken along the line 5—5 thereof.

Before explaining in detail the present invention, it is to be understood, that the invention is not limited in its application to the details of construction and arrangement of parts illustrated in the accompanying drawing, since the invention is capable of other embodiments and of being practiced or carried out in various ways. Also, it is to be understood, that the phraseology and terminology employed herein is for the purpose of description and not limitation.

In the drawings, the numeral 10 indicates a hunter having an arrow quiver 12, made in accordance with the principles of the invention, detachably strapped on his back. The hunting arrow quiver 12 comprises a lower supporting arm, generally indicated by the numeral 14, and, which may be made from any suitable light-weight metal, plastic, fiber board, or the like. The lower supporting arm 14 is fixedly connected, as by welding, to a vertical lower flat elongated supporting member 16 made from the same material as the supporting arm 14. The supporting member 16 is provided with a pair of laterally spaced longitudinally extending ferrules or projections 18 and 20.

45 The lower supporting arm 14 comprises a bottom wall 22 and an integral upwardly extended peripheral side wall 24. As shown in Fig. 3, the lower supporting arm 14 is substantially oval in shape and flat on one side, however, it will be understood that this supporting arm or member may be formed with any other desirable cross-section shape. The side wall 24 forms a recess with the bottom wall 22 in which is fixedly mounted, by any suitable means, a piece of elastic material 26, such as sponge rubber or the like. Fixedly mounted on the upper surface of the sponge rubber 26 is a plurality of spaced apart rings 28 which are made from any suitable material, such as leather, plastic, or light-weight material. As shown in Fig. 2, the rings 28 are adapted to slidably receive and hold in position, the lower or 55 tufted end 30 of the hunting arrows, generally indicated by the numeral 32.

50 As is shown in Figs. 2 and 4, the quiver 12 includes an upper flat elongated supporting member 34 which is provided with a pair of longitudinally extending spaced apart ferrules 36 and 38, which are adapted to be slidably engaged in the ferrules 18 and 20, respectively, of the lower supporting member 16. The outer longitudinal edges 40 of the upper supporting member 34 are folded inwardly over the longitudinal edges 42 of the lower supporting member 16. The upper supporting member 34 is provided with a pair of longitudinally disposed slots 44, on each side thereof, as shown in Fig. 2. The lower

supporting member 16 is provided with a pair of bolts, as 48, along each side thereof, which are adapted to pass through the slots 44 and be adjustably secured in any position in said slots, by means of the nuts 50. The numeral 52 indicates the upper edge of the lower supporting member 16, and, the numeral 54 indicates the lower edge of the upper supporting member 34.

As shown in Fig. 2, an upper supporting arm, generally indicated by the numeral 56, is fixedly mounted on the front side of the upper elongated supporting member 34, by any suitable means, and in a manner similar to that for the lower supporting arm 14. The upper supporting arm 56 would be made from the same material as the lower supporting arm 14. The upper supporting arm 56 comprises a top wall 58 and an integral downwardly extended peripheral wall 60, which coacts with the top wall 58 to form a downwardly facing recess in which is fixedly mounted a piece of an elastic material 62, such as sponge rubber, or the like. Fixedly mounted on the lower downwardly facing side of the elastic material 62 is a plurality of rings or annular members 64, which are spaced apart and in alignment with mating rings among the plurality of rings 28 on the lower supporting arm 14. As shown in Fig. 2, the rings 64 are adapted to slidably receive the upper ends 66 of the hunting arrows 32, and, to hold them in position in the quiver. The quiver 12 is adapted to be adjustably mounted on the back of the hunter 10 by means of a pair of shoulder straps 68 and 70, one pair of ends of which are connected to the upper set of bolts 48, and the other pair of ends 72 and 74 of which are passed under the arms of the hunter and are secured to the lower pair of bolts 48. These shoulder straps may be provided with suitable adjustment means, as 76. The quiver is further provided with a strap adapted to pass around the waist of the hunter with the ends 78 and 80 thereof being adapted to be fixedly mounted on the lower pair of bolts 48 in the quiver supporting members 16 and 34.

The quiver is provided with a cover, generally indicated by the numeral 82, and which may be made from any suitable flexible material, as canvas, plastic, or the like. The cover is adapted to be fixed around the open-sides of the upper supporting arm 56, and, to be secured thereto by any suitable means, as by the snap members 84. The cover 82 does not extend down completely to the lower supporting arm 14 but terminates a few inches thereabove, as indicated by the numeral 86. As viewed in Figs. 1 and 2, the cover 82 is preferably fastened to the elongated supporting members 16 and 34 along the left side thereof by any suitable means, as by the snaps 88, and, said cover is substantially loose along the right side thereof, to permit the hunter to move this side and get into the quiver to take an arrow therefrom. The right side of the cover 82 is held against the quiver in a loose manner by means of the end 80 of the waist strap passing through an aperture 89 in said cover.

In use, the quiver 12 would be detachably mounted on the back of the hunter 10, as shown in Fig. 1, and, with the tufted ends 30 of the arrows disposed in the lower position. In order to remove an arrow from the quiver, the hunter would merely place his hand by his side and then reach backwardly into the quiver, which

movement may be easily made by the hunter. The lower end of an arrow is then grasped and such arrow is moved upwardly a slight distance to a position shown by the arrow 90 in Fig. 2. Since the elastic material yields under such movement of the arrow, the lower end of the arrow 90 may then be swung outwardly from the lower supporting arm 14 and the arrow then completely removed from the quiver by an easy downward and forward movement of the hunter's arm. The hunter has then merely to continue the movement of his arm to bring the arrow into a position for instant mounting on the bow for immediate discharge thereof in a minimum of time.

Experience has shown that a quiver made in accordance with the present invention permits a hunter to move through the forest without entangling the quiver with the underbrush, and, with a minimum display of the bright colors of the arrows. With a quiver of the present invention, a hunter may remove an arrow therefrom and shoot it in a shorter time than has been heretofore possible with similar type arrow quivers. It will be seen, that the present hunting arrow quiver may be made to hold as many arrows as desired, and that each arrow so held or retained may be removed from the quiver without disturbing the others.

While it will be apparent that the preferred embodiment of the invention herein disclosed is well calculated to fulfill the objects above stated, it will be appreciated that the invention is susceptible to modification, variation and change without departing from the proper scope or fair meaning of the subjoined claim.

What is claimed is:

A hunting arrow quiver comprising: a lower supporting arm; a lower elongated member adapted to carry said lower arm; an upper elongated member slidably mounted on said lower elongated member; means adjustably securing said elongated members together; an upper supporting arm on the upper end of said upper elongated member; said arms having a recess on their inner adjacent sides; an elastic means in said recesses adapted to releasably retain a plurality of arrows between said arms; each of said elastic means being provided with a plurality of locating parts for retaining the arrows in predetermined positions on said supporting arms; said quiver being provided with a cover for enclosing the arrows carried thereby, which is adapted to be secured to the top arm and to extend downwardly and adjacent to, but not in contact with said lower arm, and to be secured to said quiver along one side of said elongated members and to be in engagement with the other side of said elongated members but being free to be swung away from the quiver to permit the user to easily withdraw an arrow from the quiver.
